UNITED STATES PATENT OFFICE.

THOMAS S. PATTERSON, OF ROSEMONT, PENNSYLVANIA, ASSIGNOR OF ONE-HALF TO CLARENCE E. WILSON, OF BRYN MAWR, PENNSYLVANIA.

NAPPING-MACHINE.

1,186,431.

Specification of Letters Patent.

Patented June 6, 1916.

Application filed May 17, 1913. Serial No. 768,249.

To all whom it may concern:

Be it known that I, THOMAS S. PATTERSON, a subject of the King of Great Britain and Ireland and the Isle of Man, residing in Rosemont, county of Montgomery, State of Pennsylvania, have invented certain Improvements in Napping-Machines, of which the following is a specification.

This invention relates to certain improvements in machines for raising the nap on fabrics and particularly blankets which have been washed.

One object of the invention is to construct a machine particularly adapted for use in laundries, which will properly raise the nap on both surfaces of the fabric as it passes through the machine.

A further object of the invention is to provide means for raising the nap on each face, first in one direction and then in the other direction so that, after a blanket has passed through the machine, the nap is evenly raised on both surfaces of the blanket or other fabric.

A still further object of the invention is to stretch the blanket as it is fed to the machine so that it will be in proper condition after it leaves the machine.

In the accompanying drawings: Figure 1 is a front view of my improved napping machine; Fig. 1^a is a view of the driving shaft, being a continuation of Fig. 1; Fig. 2 is an end view of my improved machine; Fig. 3 is a transverse sectional view on the line a—a, Fig. 1; Fig. 4 is a transverse sectional view on the line b—b, Fig. 1; and Fig. 5 is a side view of one of the clamps.

Referring to the drawings, 1—1 are the side frames of the machine connected together and braced in any suitable manner. These side frames support the bearings for the several shafts.

2 is the main cylinder, which is clothed with card clothing 3 in which the teeth are turned, as clearly illustrated in Fig. 3 so that the fabric will be fed by the back of the teeth, but when the nap is being raised by the mechanism described hereinafter, then these teeth act to hold the fabric during the napping process.

4 is an inclined platform at the front of the machine on which the blanket is spread, and preferably stretched, and over which the blanket is fed into the machine. Directly above the platform 4 is a spreader 9,

which properly spreads and stretches the blanket on the platform before the first feed roll engages it in order to feed it through the machine. Pivotaly mounted on the frame of the machine is a frame carrying the feed rolls. The first roll 5 is directly above the upper end of the platform and has card clothing 6 thereon with the teeth projecting, as shown, so that the wheel will engage the fabric and will feed it positively forward into the space between the second feed roll 7 and the cylinder 2. This second feed roll has card clothing 8 with the teeth bent in the same direction as the teeth of the roll 5 so as to continue the feeding of the fabric over the cylinder 2. The teeth of the drum merely act to hold the cloth in positive engagement with the teeth of the second feed roll and also act, as before stated, to prevent the napping mechanism from feeding the blanket at a greater speed than the feed mechanism will allow. A plain roll 48 is located so as to hold the fabric onto the cylinder 2 after its leaves the feed roll 7.

10 is the first feeding and napping cylinder and 11 is the second feeding and napping cylinder. The cylinder 10 has card clothing 12 thereon with the teeth turned, as indicated, to engage the nap on one side of a blanket and to raise the nap as the blanket is fed through the machine. The cylinder 11 has card clothing 13 with teeth turned in the same direction as the teeth 12 and will raise the nap on the opposite side of the fabric. These two cylinders only raise the nap in one direction.

I mount two counterbalanced segments 14 and 15, one on one side of the line of travel of the fabric and the other on the opposite side. The segment 14 has card clothing 16 with the teeth turned toward the feed cylinders and the segment 15 has card clothing 17 with the teeth turned in the same direction and it will be seen that as the blanket, for instance, is fed forward through the machine the card clothing on the segments 14 and 15 raises the nap on both sides of the fabric in one direction and as the blanket passes the cylinders 10 and 11, which rotate at a greater speed than the travel of the blanket through the machine, the nap is raised in the opposite direction to that in which it was raised by the segments 14 and 15. Consequently, when the

blanket is delivered from the machine, the nap is properly raised on both sides thereof.

It will be understood that any suitable mechanism may be used for imparting movement to the several elements, as the main object of the invention is to provide a machine in which a blanket or other fabric will be fed therethrough at a given speed, and the nap on the fabric will be raised first 10 in one direction and then in the opposite direction.

In order to disengage the fabric from the teeth of the cylinder 2, I provide guards 18 which are in the form of wires, in the present instance, arranged to enter the spaces at intervals between the teeth. These guards are secured to blocks 19 carried on a bar 20, adjustably mounted in a slot 21 in the side frames 1. I also show guards 22 spaced a 20 given distance apart and arranged to move the fabric away from the cylinder 10. These guards are similar to the guards 18 and are mounted on blocks 23 secured to a bar 24, which is adjustably mounted in a slot 25 in 25 the frame 1.

Below the cylinder 11 is a beater 26 consisting of a shaft 27 on which are blades 28. This beater is driven from the shaft 29 of the cylinder 11 by a chain 30 which passes 30 around sprocket wheels on the said shafts so that as the shaft 29 is rotated, a rotating motion will be imparted to the beater which acts to force the fabric from engagement with the teeth of the cylinder 11 as it passes 35 through the machine. In some instances, beaters may be substituted for the guards 22 and 18, or guards may be substituted for the beaters without departing from the essential features of the invention.

40 The spreader 9 is mounted on a cross bar 31 extending over the platform 4 and adapted to bearings 32 at each edge of the platform. Adjustably mounted on the bar are sleeves 33, which can be clamped thereto 45 and held in the position to which they are adjusted. Pivottally hung from the sleeves 33 are diagonally arranged arms 34, which are connected together by a pivot pin 35. The arms 34 are T-shaped in cross section 50 and the broad portion of each arm rests directly above the platform so that when a blanket is located on the platform under the arms, the weight of the spreader and the diagonal arrangement of the arms spreads 55 the blanket evenly over the platform and it enters the machine in an unwrinkled condition. I may provide means for stretching the blanket on the platform before it enters the machine and clamps may be used to hold 60 the stretched fabric and may be made adjustable as described hereinafter.

In the present instance, the mechanism is driven as follows: Mounted on a bracket 35, projecting from one of the side frames, are 65 the bearings 36 for the driving shaft 37 hav-

ing fast and loose pulleys 38 and 39 thereon, as illustrated in Fig. 1^a. On the shaft 37 is a pinion 40 which meshes with a gear wheel 41 on the main driven shaft 42 on which is mounted the cylinder 2. The shaft is 70 adapted to bearings in a standard 43 projecting from the bracket 35 and is also mounted in bearings 44 on the side frames 1.

On the shaft 42 is a gear wheel 45 which meshes with a pinion 46 on a shaft 47 adapted to suitable bearings on extensions 69 of the main frame of the machine, and carrying the plain roll 48. A gear wheel 49 is mounted on the shaft 47 and meshes with an intermediate gear wheel 50 on a shaft 51 80 mounted in boxes 52 arranged to slide in slots in the frame 53. The gear wheel 50 meshes, in turn, with a gear wheel 54 on the shaft 55 carrying the roller 7. The shaft 55 is adapted to boxes 56 arranged to 85 slide in slots 58 in the frame 53. Each box 56 is held in position by a spring 59 mounted between a set screw 60 and its box so that while the roller 7 is pressed forward by the springs, it can yield when necessary. 90 Mounted on a shaft 61 is a gear wheel 62 which meshes with the gear wheel 54 on the shaft 55. The shaft 61 is mounted in boxes 63 arranged to slide in slots 64 in said frames 53. The gear wheel 62, in turn, 95 meshes with a gear wheel 65 on the shaft 66 carrying the first feed roll 5, which is mounted in fixed bearings in the frames 53. In order to allow the second feed roll 7 to yield without jamming the gear wheels 49 100 and 62, I connect the shaft 55 to the shafts 51 and 61 by arms 67 and 68 respectively, so that as the shaft 55 yields, it will cause the boxes 52 and 63 to move in their slots.

The shaft 47 acts as the pivot for the 105 frames 53 which are connected together by the shafts so that they can be turned up in unison to allow the fabric to be adjusted thereon. Any suitable mechanism may be used for turning the frames 53 on their pivots. In the present instance, I have shown levers 70 pivoted at 71 to the main frame. The long arms of these levers are connected together by a bar 72 and the short arm of each lever is connected by a link 73 110 to one of the frames 53 so that on turning the lever 70 on its pivot, the whole frame structure can be raised or lowered.

The segment 14 extends full width of the 115 cylinders 10 and 11 and is secured to the arms 74 mounted on a shaft 75 adapted to bearings adjustably mounted in a slot 76 in the frames 1. On each arm 74 is a rear extension 77 having an adjustable weight 78 which is arranged to balance the segments.

The segment 15 is carried by arms 79, which are mounted on a shaft 80 adapted to bearings adjustably mounted in a slot 81 in the frames 1 and on each arm 79 is a 120

rear extension 82 having an adjustable weight 83. These two segments have card clothing in the present instance mounted thereon and the teeth of the card clothing 5 act as combs to raise the nap of the blanket, or other fabric, as it is fed through the machine and the weights allow the segments to yield and to engage the nap without breaking the fibers, which might occur if 10 the segments were positively reciprocated or rotated.

The cylinder 10 is carried by a shaft 84 mounted in bearings 85 adjustable in the slot 86 in the frames 1. On one end of the 15 shaft 84 is a bevel wheel 87 which meshes with a bevel wheel 88 on a diagonal shaft 89 in a bearing 90, projecting from one of the side frames 1. At the upper end of the shaft 89 is a bevel pinion 91, which 20 meshes with a bevel gear wheel 92 secured to the shaft 42 so that the shaft 84 is positively driven from the shaft 42 through the diagonal shaft 89.

The shaft 29, on which the cylinder 11 is 25 mounted, is driven from the shaft 42 by a chain belt 93, in the present instance, which passes around a sprocket wheel 94 on the shaft 42 and around a sprocket wheel 95 on the shaft 29, so that the shaft 29 is positively 30 driven by the belt 93. The two shafts 84 and 29 are preferably driven at the same speed and the speed is such that the portion of the blanket, or other fabric, between the cylinders 10 and 11 and the feed cylinder 2, 35 will be held taut by the action of the cylinders so that the segments will properly comb the fibers as the fabric passes them.

The clamp which I prefer to use to stretch the blanket, or other fabric, is shown in 40 Fig. 5 and consists of a presser plate 96 on a spindle adapted to a frame 97 on which is a coiled spring 98 for raising the plate. A cam lever 99 is used to force the plate onto the fabric. The frame has a T-head 100 adapted to a slot 101 in the platform 4 so that when the head is passed through the slot and the frame turned, the frame will be locked to the platform. There are a series of slots 101 on the platform so that the 50 clamps can be adjusted to stretch blankets differing in size.

I preferably provide two clamps at the upper edge of the platform and one of these clamps is adjustable with respect to the other. I may locate clamps at the lower edge of the platform if it is found desirable to hold the blanket at four points prior to adjusting the spreader and the feed rolls.

In the present instance, I have located a 60 table 102 at the rear of the machine directly back of the cylinder 10 so that fringe at the edge of fabrics can be combed out by placing the fabric on the table and allowing the fringe to be engaged by the clothing 65 of the said cylinders.

The operation is as follows: A blanket, for instance, after being cleansed, is passed through the machine, preferably in a damp condition in order that the nap may be raised on both sides thereof, and after the 70 nap is raised the blanket is suspended until dry. Prior to placing the blanket on the platform the frame carrying the feed rolls is raised. The spreader is also lifted and the two clamps are adjusted to accommodate 75 a blanket of a given size. One upper corner of the blanket is secured by a clamp and the blanket is then stretched and engaged by a clamp at the opposite corner, after which the frame and the spreader are lowered; the 80 spreader resting on the surface of the blanket and the first feed roll engaging the fabric. The clamps are then raised to release the blanket and the machine set in motion. 85

The two segments 14 and 15 are turned out of the path of the blanket so that it can fall by gravity between the napping cylinders 10 and 11, the teeth of which engage the blanket and stretch it, as the napping 90 cylinders revolve at a greater speed than the feed cylinder 2. The segments are then turned so that the teeth engage the nap of the blanket. As the blanket is fed through the machine the segments comb the nap on 95 both sides of the blanket in one direction and as it passes between the cylinders 10 and 11 the nap is combed in the opposite direction. The cylinder 2 positively feeds the blanket through the machine and holds it 100 against the action of the teeth on the napping cylinders so that while these cylinders tend to feed the blanket and to place tension thereon to allow the segments to comb the nap, they cannot feed the blanket at a greater speed than the surface speed of the feed cylinder 2. The blanket is stripped from the cylinder 2 by the fingers 18 and from the cylinder 10 by the fingers 22 while the beaters force the blanket out of engagement with the cylinder 11. After the 105 blanket passes through the machine, it is suspended and dried and the nap will be evenly raised on both sides thereof and will have the soft finish common to blankets before being laundried. 110

While the invention is particularly adapted for raising the nap on a laundried blanket, it can be used for raising the nap on one or both sides of any fabric. 115

I claim:

1. The combination in a napping machine, of a feed roll and a feed cylinder for feeding the fabric through the machine; two napping cylinders having teeth thereon bent in the same direction for engaging and raising the nap on both sides of the fabric; and means intermediate the napping cylinders and the feed cylinder having teeth arranged in a direction opposite the teeth on the nap. 120

ping cylinders and located one on one side of the line of the fabric and one on the opposite side thereof, which also act to raise the nap on the fabric.

5. 2. The combination in a napping machine, of means for feeding the fabric; a rotating napping cylinder having teeth arranged in one direction; a stationary toothed segment located between the napping cylinder and the feed mechanism and having teeth arranged in a direction opposite to the direction of the teeth of the napping cylinder and engaging the nap of the fabric; and means for allowing the said segment to yield.

10. 3. The combination in a napping machine, of means for feeding the fabric; a napping cylinder; segments having card clothing thereon forming teeth for engaging the nap of the fabric; counterbalanced arms carrying the segment; and a pivot for said arms so that as the fabric is fed through the machine, the nap will be engaged by the teeth on the segments and will be raised in one direction.

15. 4. The combination in a napping machine, of feed mechanism for feeding the fabric through the machine; two cylinders having card clothing thereon and arranged to engage the nap of the fabric to raise it in one direction; means for driving the said cylinders at a greater speed than the feed mechanism so as to apply tension to the fabric between the feed mechanism and the cylinders; and napping mechanism located between the feed mechanism and the napping cylinders having teeth extending in the opposite direction from that of the cylinders so that, as the fabric passes the napping mechanism, the nap will be raised in one direction and when it passes the cylinders the nap will be raised in the opposite direction.

20. 5. The combination in a napping machine, of a feed roll and a feed cylinder over which the fabric is passed so as to positively feed the fabric forward through the machine; two napping cylinders located beyond the feed cylinder and spaced apart to allow the fabric to pass between them, each napping cylinder having card clothing thereon; these napping cylinders being driven at a greater speed than the feed cylinder; and two segments, one located on one side of the fabric and the other on the opposite side, each segment being pivotally mounted and having card clothing thereon; the teeth being arranged in an opposite direction from the teeth on the napping cylinders.

25. 6. The combination in a napping machine, of a feed cylinder having card clothing thereon, the teeth extending rearwardly; a frame pivotally mounted on the main frame of the machine so that it can be turned on its pivot; a driven feed roll carried by the

frame and located in close proximity to the feed cylinder so that when the frame is in its normal position the fabric will be engaged by the roll and by the teeth of the cylinder; and means for napping the fabric after it leaves the feed cylinder, the teeth of the feed cylinder holding the fabric against the action of the napping means.

7. The combination in a napping machine, of side frames; a shaft; a feed cylinder mounted on the shaft and having card clothing thereon; a feed roll also having card clothing and yieldingly mounted on the frame, the teeth of the card clothing on the feed cylinder being inclined rearwardly and the teeth of the card clothing on the feed roll being inclined in the direction of movement of the fabric; and means beyond the feed cylinder for raising the nap on both sides of the fabric as it passes through the machine.

8. The combination in a napping machine, of side frames; a shaft mounted therein; a feed cylinder mounted on the shaft and having card clothing thereon; an inclined platform located at the front of the machine; two feed rolls; means for driving said rolls; each of said rolls having card clothing one being mounted above the platform and the other above the feed cylinder, the teeth on the feed cylinder being so arranged as to prevent the movement of the fabric at a greater speed than the surface speed of said cylinder; a rotating napping cylinder having teeth thereon and arranged to engage the nap on the fabric beyond the feed cylinder; and intermediate napping mechanism having teeth arranged in a direction opposite to the teeth of the napping cylinder so as to raise the nap as the fabric passes through the mechanism.

9. The combination in a napping machine, of a platform on which the fabric is placed; a feed cylinder over which the fabric is passed; card clothing on said cylinder; teeth arranged to prevent the fabric from moving more rapidly than the surface speed of the cylinder; a pivotally mounted frame; means for raising and lowering the frame; feed rolls carried by the frame; gearing by which the feed rolls are driven from the main shaft, one of said rolls being yieldingly mounted in the bearings; and two oppositely disposed cylinders having card clothing thereon and driven at a greater speed than the feed mechanism to raise the nap on the fabric as it passes through the machine.

10. The combination in a napping machine, of a feed cylinder; teeth thereon; a feed roll acting in conjunction with the cylinder to feed the fabric through the machine; means for raising the nap on the fabric; a platform in front of the machine; a bar extending across the upper end of the plat-

form; a V-shaped spreader having two arms pivotally connected at their lower ends, each frame being adjustably mounted on the bar; and a spreader acting to spread the 5 fabric on the platform before it is engaged by the feeding mechanism.

11. The combination in a napping machine, of a feed cylinder; a feed roll having teeth arranged to engage and feed a fabric 10 through the machine; means located beyond the feed roll for napping the fabric; an inclined platform located in front of the machine; a bar extending across the upper portion of the platform; two sleeves adjustably mounted on the bar; means for retaining the sleeves in the position to which they are adjusted; and a spreader consisting of 15 two arms pivotally connected, one arm being pivotally attached to one sleeve and the other arm being pivotally attached to the 20 other sleeve so that the width of the spreader can be varied by adjusting the sleeves on the bar.

12. The combination in a napping machine, of two side frames; a driven shaft 25 mounted in bearings in the upper portion of the frame; a feed cylinder having teeth thereon and secured to the driven shaft; a pivotally mounted frame located above the feed cylinder and having two feed rolls, one yieldingly mounted in said frame; means for raising and lowering the said 30 frame; two napping cylinders having teeth; a shaft on which the napping cylinders are 35 mounted; bearings for each shaft, the frames being slotted for the bearings; two segments, one located on one side of the line of the fabric and the other on the opposite side, each segment having card clothing 40 theron; arms carrying the segments; a shaft on which the arms are mounted; and bearings for the shaft adjustably mounted in slots in the frame so that the segments can be adjusted with respect to the fabric. 45

13. The combination in a napping machine, of side frames; a driven shaft mount-

ed therein; a feed cylinder mounted on the shaft; a feed roll acting in conjunction with the said cylinder to feed the fabric through the machine; a pivoted frame carrying the 50 feed roll; a lever pivotally mounted on the main frame; a link connecting the lever with the pivoted frame so that, when the lever is actuated, the pivoted frame is raised and lowered; and means, beyond the feeding 55 mechanism, for raising the nap on the fabric.

14. The combination in a machine for raising the nap on fabrics, of a platform; a pivoted spreader located above the platform; a feed 60 cylinder over which the fabric is passed; a pivoted frame; a feed roll mounted on the frame and acting in conjunction with the feed cylinder to feed the fabric through the machine; means for raising the nap on the 65 fabric; and clamps at each upper edge of the platform for securing the blanket after being stretched on the platform and prior to being engaged by the feed roll.

15. The combination in a machine for 70 raising the nap on fabrics, of a feed cylinder; an inclined platform in advance of the feed cylinder; a frame mounted above the feed cylinder; a feed roll carried thereby; a spreader located above the platform; a 75 clamp at the upper edge of the platform at one side; an adjustable clamp located on the opposite side of the upper edge of the platform for engaging the fabric after being stretched, the said clamps being so located that when the frame is lowered the feed roll will engage the fabric so that the clamps can be released to allow the fabric to be fed in the machine; and means for raising the nap on the fabric. 80

In testimony whereof, I have signed my name to this specification, in the presence of two subscribing witnesses.

THOMAS S. PATTERSON.
